UNITED STATES PATENT OFFICE.

FREDERICK J. CLIFFORD, OF CHICAGO, ILLINOIS, ASSIGNOR TO ALLIANCE COMPANY,
OF CHICAGO, ILLINOIS, A CORPORATION OF NEW JERSEY.

FLOAT-VALVE.

1,247,643.

Specification of Letters Patent. Patented Nov. 27, 1917.

Application filed February 19, 1917. Serial No. 149,400.

To all whom it may concern:

Be it known that I, FREDERICK J. CLIFFORD, a citizen of the United States, residing in Chicago, in the county of Cook and State 5 of Illinois, have invented a new and useful Improvement in Float-Valves, of which the following is a specification.

This invention relates in general to float valves and has more particular reference to 10 float valves provided for closet and lavatory tanks, although it will be manifest as the invention is better understood that it has other and wider application.

A principal object of the invention is the 15 provision of a float valve which will permit the tank to empty substantially of all its water at each operation of the valve. To accomplish this it is desirable that the valve and valve parts be as light as possible; that 20 is to say, that the valve be relieved as much as possible of heavy attendant parts which cause it to ride low in the water and consequently shut off while a substantial part of the water remains in the tank. The invention 25 contemplates, therefore, the valve riding nearly on the surface.

A further object of the invention is the provision of a valve of easy and positive operation,—not likely to bind on the guides 30 provided to direct its movement and not likely to become stuck upon its seat.

A still further object of the invention is the provision of a valve which will permit of the arrangement of a more effective overflow; that is to say, prior to my invention 35 the overflow for tanks of this character has been usually mounted in commercial structures alongside the valve seat and connected with the outlet by the relatively restricted 40 passage. This invention contemplates the arrangement of an overflow having a full opening from its inlet into the tank outlet. The passageway between the overflow pipe and the outlet opening usually has been provided through the part of the valve seat or 45 outlet member which is disposed above the tank bottom necessarily elevating the valve seat proper and thereby increasing the amount of water left in the tank after flushing.

This invention also has for an object the provision of a valve and attendant mechanism or parts which will permit the valve

seat to be disposed in close proximity to the bottom of the tank.

A further object of the invention is the provision of a valve possessing these and other advantages, which will be of economic construction, but which will consist of few and simple parts readily provided and assembled and not likely to require frequent or expensive repair.

A still further object of the invention is the provision of a valve mechanism for these and other advantages which may be used in 65 relatively narrow tanks and so constructed and arranged that the parts of the mechanism obstructing the interior of the tank may be readily removed to facilitate cleaning the tank and making repairs upon the 70 inlet valve mechanism as may be required.

Other objects and advantages of the invention will be apparent as it is better understood from the following description when considered in connection with the 75 accompanying drawing illustrating a preferred embodiment thereof.

Referring to the drawing,

Figure 1 is a section taken through a tank equipped with a valve embodying my present invention;

Fig. 2 is a vertical section taken through the valve and outlet opening on an enlarged scale; and

Fig. 3 is a horizontal section taken when 85 the valve proper is elevated.

For the purpose of illustrating my invention I have shown on the drawing a closet tank 11 of ordinary or any preferred construction. This tank is provided with an outlet opening 12 in its bottom through which extends a valve seat member 13. This valve seat member is preferably provided with an inner spider 14 having a hollow center through which is positioned the lower end 15 of a pipe or hollow stem 16. The lower end 15 of the overflow pipe is threaded into or otherwise secured in the hollow center of the spider so that this pipe is rigidly held and extends up an appropriate height 95 into the tank. The valve seat or outlet member 13 is provided with a valve seat member 17 at its top. This seat, being of larger diameter than the opening 12, rests upon the bushing or packing 18, the parts being held 100 in water tight relation by a nut or collar 19

threaded on the outside of the valve seat or outlet member 13.

A sleeve 21 embraces the pipe 16 and serves as an overflow pipe and is of a length appropriate to dispose the top of the sleeve above the desired water level when the tank is full and the sleeve in lower or normal position. The lower end of this sleeve is threaded as indicated at 22 and on the threaded part of the sleeve is positioned a second valve seat member 23. The valve seat member 23 and the valve seat member 17 are adapted to be positioned to form what may be termed a valve seat at the outlet, the parts being adjustable with respect to each other by reason of the threaded engagement of the member 23 with the lower end of the sleeve and providing an annular outlet opening extending about the overflow pipe.

A float valve, generally indicated at 24, embraces this sleeve and is free to slide vertically thereon. This valve is of annular form and preferably of substantially circular cross-section and is furthermore of soft or yielding material in order that the pressure of the water above it in the tank when the valve is seated will cause the valve to be pressed or sucked down upon its seat. An opening 25 in the bottom of the valve permits the valve to be more readily collapsible or yielding.

When the valve is seated it is in the position shown in Fig. 2 and is held tightly against its seat by the suction below and water above in the tank. In order that the valve may be moved to open position it is only necessary to break its connection with the seat and permit it to rise by its buoyancy on the sleeve 21. This is accomplished by lifting the sleeve and the valve member 24 a sufficient distance to start the flow of water. The sleeve or overflow pipe may be lifted by any preferred or usual flushing lever or other mechanism which can be connected by a link 26 engaging an eye 27 in a collar 28 which embraces the pipe. The collar 28 is preferably bent at one side and secured about the pipe by a connection 29 so that it may be adjusted upon the pipe at a height to facilitate connection with the link 26 or the operating mechanism, or it may be at a height to limit the rising of the float valve 24, the adjustment with respect to the operating mechanism being accomplished by bending the link 26 or substitution therefor of different links. The valve preferably consists of merely a hollow rubber ring and, if desired, a metal plate or sleeve 32 may be positioned in the opening through it to cause it to slide freely and easily on the sleeve 21. Where this sleeve is provided the valve is not accurately circular in cross-section but this is not believed to be important.

It will be manifest from the foregoing

that the pipe 16 forms a stationary guide. The sleeve 21 can be considered as a second guide or merely as the means for breaking the pressure holding the valve to its seat.

It will also be manifest that the sleeve 21 and the valve may be lifted out of the tank by silding it off the end of the pipe or stem 16 and that this stem may subsequently be unscrewed thereby easily removing all of the parts of the float valve mechanism from within the tank, leaving the interior free to be easily cleaned or repaired as occasion may require. This is of some importance since tanks of this character are frequently not more than 6" across inside and are relatively deep. If the interior is obstructed by internal mechanism cleaning is difficult if not impossible.

Since the valve is pushed from its seat and then rises by its own buoyancy instead of being lifted from above and therefore carries no upwardly extending rods or guiding parts, it can be of light construction, and since also the overflow communication is through the valve instead of through a part between the seat and bottom of the tank substantially all of the water is drained out of the tank when the valve is operated.

It is thought that the invention and many of its attendant advantages will be understood from the foregoing description, and it will be apparent that various changes may be made in the form, construction and arrangement of the parts without departing from the spirit and scope of the invention or sacrificing any of its material advantages, the form hereinbefore described being merely a preferred embodiment thereof.

I claim:

1. In a valve mechanism for a closet tank and the like, a valve seat and overflow pipe extending up centrally from said seat, a float valve slidably embracing and guided by said overflow pipe and adapted to close against said seat.

2. In a valve mechanism for a closet tank and the like, a valve seat and overflow pipe extending up centrally from said seat, a float valve slidably embracing and guided by said overflow pipe and adapted to close against said seat, said overflow pipe being movable to unseat said valve.

3. In a valve mechanism for a closet tank or the like, a valve seat comprising spaced members forming an annular outlet between them, a guide extending up from the inner of said members, and a float valve movable on said guide and into engagement with said seat.

4. In a valve mechanism for a closet tank or the like, a valve seat comprising spaced members forming an annular outlet between them, a guide extending up from the inner of said members, and a float valve movable on said guide and into en-

gagement with said seat, one of said seats being movable to break the pressure of water in said tank on said valve and permit the valve to rise on its guide under its 5 own buoyancy to permit the tank to empty.

5. In a valve mechanism the combination of a valve seat providing an outlet opening, an overflow pipe extending centrally into said outlet opening, and a float valve 10 embracing said overflow pipe movable thereon, and guided thereby in its movement to and from said seat.

6. In a valve mechanism for a closet tank and the like, a valve seat providing an outlet opening, a central guide extending up from the center of said opening, a sleeve 15 slideable on said guide, a float valve embracing said sleeve movable thereon and guided thereby into and out of closing position, 20 and means on said sleeve for lifting said valve from its seat in its initial opening movement.

7. In a valve mechanism for a closet tank and the like, a valve seat, consisting of 25 inner and outer members forming an annular passage therebetween, a stationary guide disposed through the inner of said members, an annular valve disposed about said guide and engaging said seats in closed 30 position, and means slideable with respect to said stationary guide for lifting said inner seat to relieve the valve from pressure of water in the tank and permit it to ride to floating position by its own 35 buoyancy.

8. In a valve mechanism for a closet tank and the like, the combination of a valve seat comprising outer and inner annular members, a central guide through the inner 40 annular member, a sleeve slideably embracing said guide and carrying said inner

member, and a float valve embracing said sleeve and liftable out of closing position through vertical movement of the inner member with the sleeve upon which it is 45 mounted.

9. In a valve mechanism for a closet tank or the like, a valve seat comprising inner and outer annular members, and a float valve of annular form and of substantially 50 circular cross-section adapted to close against said seats.

10. In a valve mechanism for a closet tank or the like, a valve seat comprising inner and outer annular members, and a 55 float valve of annular form and of substantially circular cross-section adapted to close against said seats, said valve being of soft, yielding material to permit it to accommodate itself to both said seats. 60

11. In a valve mechanism for a closet tank or the like, the combination of valve seats comprising inner and outer members providing an annular passageway between them, said seats being adjustable with respect to each other, and an annular float 65 valve for engaging said seats.

12. In a valve mechanism for a closet tank or the like, the combination of a tank bottom and valve seat member extending 70 only slightly above said tank bottom, an overflow pipe extending upwardly centrally of said seat, and a float valve slideably embracing said overflow and adapted to close against said seat. 75

Signed in the presence of two subscribing witnesses.
